WALTER H. WALTON AND HARRY D. TAPPAN, OF PHILADELPHIA, PENNSYLVANIA.

MATRIX-DRYING PRESS.

1,301,888.

Specification of Letters Patent. Patented Apr. 29, 1919.

Application filed April 21, 1917. Serial No. 163,758.

To all whom it may concern:

Be it known that we, WALTER H. WALTON and HARRY D. TAPPAN, citizens of the United States, residing at Philadelphia, in the 5 county of Philadelphia and State of Pennsylvania, have invented certain new and useful Improvements in Matrix-Drying Presses, of which the following is a specification.

This machine can be erected with very 10 little change upon the present installations. It enables the shrinkage of the matrix in drying to be compensated by springing pressure of the platen, whereby sufficient pressure upon the matrix and the die is always 15 maintained. Our machine is simple in construction, very quick in operation, and gives an exceedingly even pressure upon the matrix.

Matrix making machines are used to make 20 matrices for stereotyping. The die, which is the matter to be stereotyped, and may consist of type set in a frame, another stereotype, an electrotype, or any of many other things of this character or a combination of 25 them, has placed over it the matrix, which is a paper like material, which is usually pressed down on and into the die, and then placed in the matrix making machine beneath blankets and heated under the pressure 30 exerted by the machine until thoroughly dried. Textile or other yielding fabrics are placed over the die and matrix and their and the matrix shrinking occurs during the drying.

35 Figure 1 is a side elevation of the machine. Fig. 2 is a plan view of same. Fig. 3 is a side view of same up to the bottom of the cross beam of the press. Fig. 4 is a view of a die and a superimposed matrix. Fig. 5 40 is a vertical section of a compressor, and Fig. 6 is a view of the left half of the platen with the superimposed springs.

2 is the heated table usually heated by steam, and called, independently of how 45 heated, the drying table; the frame work of the press being formed of the standards 1, 1, and the cross beam 3. The vertically moving platen 5 is adapted to hold, between it and the drying table, the die 17, the matrix 50 and the compressible textile or other 55 material technically known as the blankets 18. The platen 5 is provided with positively acting mechanism and springing mechanism for driving down the platen on the blankets, matrix and die. The most convenient form of which I am at present aware 55 of combining and constructing these two mechanisms is as follows: A spider 6 has placed between it and the platen, the springs 8. By distributing these springs in the 60 form of a circle (see particularly Fig. 6) a very even pressure is given to the platen especially as springs can be secured of standard shape and elasticity. Between the spider and the beam of the press is a hydraulic 65 compressor 24 which for reasons seen below we regard as the best device for giving the positive pressure of the platen upon the blankets, matrix and die. The base 31 of this compressor 24 rests on the spider 6. 70 The gage 27 indicates the pressure exerted by the compressor 24. The mechanism of a good form of the compressor is shown in Fig. 5. The head 25 is screwed to the concentric cylinders 34, 36. The cylinder 35, 75 fits between them and is closed at the bottom. The plug 37 carries the valve 32 held against its seat by the spring 33. The bucket 37 is carried by the cylinder 36 and has the washer 39 fitting against the inside 80 of the wall of the cylinder 35. The plunger 29 has the valve 313, the head 27 is operated in any usual way. The head is manipulated by the handle 23, which, when in normal position, has the downward travel imparted 85 to it by the plunger 29 limited by the stop 26 impinging against an enlarged part of the arm 23, but which, when moved from normal position allows the plunger 29 to be depressed until this depression opens both of 90 the valves 32 and 313. This construction gives the press a convenient quick release mechanism for relieving the compression on the platen instantly. The gage 37 is connected beneath the valve 32. The standard 95 30 has a socket in which the cylinder 34 fits. A chock 28 can be placed between the compressor and the beam 3 if thought desirable. The combined action of the hydraulic compressor and the springs has very 100

useful results. The thrust of the compressor is directly downward and can be halted at any point where the exact amount of compression desired has been attained. The 5 direct downward thrust has especial advantages in our device; among them that although necessarily the platen is brought at first into a light contact with the matrix, and its pressure on the matrix then increased 10 by the compression of the springs, the matrix will not be disturbed by any lateral or torsional tendency of the compressor. Such movement would give an irregular motion to the springs and would frequently blur and 15 spoil the matrix. The varying thickness of the material to be pressed and the variation to some extent of the pressure to be exerted upon the matrix makes frequently very inconvenient a compressor with a fixed length 20 of travel.

We prefer to lift the platen 5 by hand assisted by a counter balance. The form of counter balance we adopt in practice is 25 springs 9, 9 secured by the staples 7, 7 and adjustably attached to the beam 3 by the tie rods 10, 10 which are adjustably held by the nuts 15, 15. We prefer that the counter balance should not be sufficient to lift the platen 5, so that the latter, unless otherwise 30 supported will sink of its own weight upon the blanket 18, matrix 191 and die 17. The hand mechanism for lifting the platen 5, consists in practice of the head 16, movable vertically and provided with guides 40, 40, 35 and with tie rods 11, 11, by which the platen is lifted. These rods can be secured to the head by nuts 14, 14. The head is lifted by a toggle mechanism very conveniently consisting of a handle 19 secured to the shaft 40 having bearings in the beam 3, and having the arm 12 connected by the pivot 21 to the arm 13, which is secured to the shaft 22. The shaft 22 has bearings in the head 16. The shafts 20 and 22 extend through the 45 beam 3 and the head 16 and have the arms 121 and 131 secured to them. These arms are pivoted similarly to the arms 12 and 13 and the toggle can be suitably stopped just past dead center.

50 The platen 5 being raised, the toggle can be pushed past dead center, the plunger 29 being depressed so as to open both valves 32 and 313, the platen will settle down of its own weight on the blanket 18, the matrix 191 and the die 17. The compressor is then brought into action, and the compression continued until the desired pressure is attained, which will be indicated by the gage 27. If the gage indicates a lowering of the 55 pressure through the too great relaxing of the springs caused by the shrinking of the blanket, and matrix, the pressure can be increased by the compressor. Of course, the 60 pressure through the too great relaxing of the springs caused by the shrinking of the blanket, and matrix, the pressure can be increased by the compressor. Of course, the springs are made of such strength and elas-

ticity that no need will exist once the pressure is applied for any action of the compressor, in practice.

When the matrix has been dried, the plunger 29 can be depressed opening the valves 32 and 313 and the platen is easily lifted 70 by the toggle.

We claim:

1. In a matrix drying press, the combination with the drying table, press frame and platen, of a positive acting hydraulically 75 operated compressor having a direct downward thrust and elastic yielding devices operatively situated between the platen and the press frame.

2. In a matrix drying press the combination with the drying table, press frame and platen of a positively acting compressor and elastic yielding devices operatively situated between the press frame and the platen and an independently operated platen lifter. 80

3. In a machine for drying matrices, the combination with the drying table, press frame and platen, of a counterbalance for the platen, a positively acting compressor, elastic yielding devices operatively situated 90 between the platen and the press frame and a platen lifting mechanism.

4. In a matrix drying press, the combination with the drying table, the press frame and platen of a positively acting hydraulic 95 compressor, having a directly downward thrust, yielding devices operatively situated between the press frame and the platen, and quickly acting pressure release mechanism, having its pressure release devices operative 100 at position of maximum compression of the press.

5. In a matrix drying press the combination with the drying table, the press frame, and the platen of a positively acting compressor, an elastic yielding mechanism operatively situated between the press frame and the platen, counterbalance springs placed 105 between the frame and the platen, and a platen lifter. 110

6. In a matrix drying press, the combination with the drying table, the press frame and platen of a positively acting compressor, and elastic yielding devices operatively situated between the press frame and the 115 platen, a counterbalance for the platen, and a toggle mechanism for lifting and lowering the platen.

7. In a matrix drying press, the combination with the drying table, press frame and 120 platen of a compressor, operative connections between the press frame and the platen, a counterbalance for said platen, a head connected to the platen by links and a toggle mechanism for raising the platen.

8. In a matrix drying press, the combination with the drying table, press frame and platen of a compressor operative connec- 125

tions between the press frame and the platen, a counterbalance for said platen and an independent mechanism for raising said platen, the counterbalance being insufficient in itself to raise the platen.

9. In a matrix drying press, the combination of the frame, bed, and platen, of a positively acting hydraulic compressor, having

a direct downward thrust, a spider, and springs between the spider and the platen, 10 and arranged approximately in a circle.

In testimony whereof we affix our signatures.

WALTER H. WALTON.
HARRY D. TAPPAN.
